[57] CLAIM

The ornamental design for a column for nestable crate with handle, as shown and described.

DESCRIPTION

FIG. 1 is a side elevational view of a column for nestable crate in accordance with our new design;

FIG. 2 is a top plan view of the column for nestable crate of FIG. 1;

FIG. 3 is a bottom plan view of the column for nestable crate of FIG. 1;

FIG. 4 is a side elevational view of the inside of the column for a nestable crate of FIG. 1; and,

FIG. 5 is a cross sectional view of the column for nestable crate taken along line 5—5 of FIG. 2.

The broken line showing of a crate in FIGS. 1-4 is for illustrative purposes only and forms no part of the claimed design.
